(57) CLAIM

The ornamental design for a bottle for containing a cosmetic as shown and described.

DESCRIPTION

FIG. 1 is a front perspective view of a bottle for containing a cosmetic, and a cap, showing our new design;

FIG. 2 is a front elevational view of the bottle and cap of FIG. 1;

FIG. 3 is a rear elevational view of the bottle and cap of FIG. 1;

FIG. 4 is a right side elevational view of the bottle and cap of FIG. 1;

FIG. 5 is a left side elevational view of the bottle and cap of FIG. 1;

FIG. 6 is a top plan view of the bottle and cap of FIG. 1;

FIG. 7 is a bottom plan view of the bottle and cap of FIG. 1;

FIG. 8 is a front perspective view of the bottle of FIG. 1;

FIG. 9 is a front elevational view of the bottle of FIG. 1;

FIG. 10 is a rear elevational view of the bottle of FIG. 1;

FIG. 11 is a right side elevational view of the bottle of FIG. 1;

FIG. 12 is a left side elevational view of the bottle of FIG. 1;

FIG. 13 is a top plan view of the bottle of FIG. 1; and,

FIG. 14 is a bottom plan view of the bottle of FIG. 1.

The evenly-spaced broken lines in the drawings are included for the purpose of illustrating the cap that forms no part of the claimed design. The dot-dash-dot broken line in the drawings is included for the purpose of defining the boundary of the claim, it being understood that the region within the dot-dash-dot broken line and the dot-dash-dot broken line itself form no part of the claimed design.
